UNITED STATES PATENT OFFICE.

WILLIAM N. MARR, OF SPOKANE, WASHINGTON.

DESIGN FOR A PRICE-CARD HOLDER.

52,333.

Specification for Design.

Patented Aug. 27, 1918.

Application filed May 16, 1918. Serial No. 235,048. Term of patent 14 years.

To all whom it may concern:

Be it known that I, WILLIAM N. MARR, a citizen of the United States, residing at Spokane, in the county of Spokane, State of Washington, have invented a new, original, and ornamental Design for a Price-Card Holder, of which the following is a specification, reference being had to the accompanying drawing, forming a part thereof.

The first figure is a perspective view of the price card holder, showing my new design, and

The second figure is an end view of the same.

I claim:

Price card holder as shown for shelving and counters.

WILLIAM N. MARR.

Witnesses:

E. BROYLES,
GUY E. SAVAGE.
